United States Patent Office.

JAMES E. HOOPER, OF WOODBERRY, MARYLAND, AND BENJAMIN ARNOLD,
OF EAST GREENWICH, RHODE ISLAND.

Letters Patent No. 80,863, dated August 11, 1868.

IMPROVEMENT IN SPINNING-MACHINE.

The Schedule referred to in these Letters Patent and making part of the same.

TO WHOM IT MAY CONCERN:

Be it known that we, JAMES E. HOOPER, of Woodberry, in the county of Baltimore, and State of Maryland, and BENJAMIN ARNOLD, of East Greenwich, in the county of Kent, and State of Rhode Island, have invented certain new and useful Improvements in Machines for Spinning and Twisting Cotton, Wool, and other Textile Materials; and we do hereby declare that the following is a full and correct description thereof, reference being had to the accompanying drawings, and to the letters of reference marked thereon.

In all the figures the same letters are used to indicate similar parts.

Figure 1 is a perspective view of a part of a front of a spinning-frame.

Figure 2 is a vertical cross-section of the same.

Figure 3 is an enlarged front view of the attachment for holding and putting on the empty bobbins.

Figure 4 is a vertical longitudinal section of the ring-rail.

Figure 5 is an enlarged view of a part of the ring-rail.

Figure 6 is a top view of fig. 3.

Our improvements consist of alterations and additions to a spinning or twisting-frame, for the purpose of removing the bobbins of yarn when full, and supplying their places by empty bobbins, a process usually called "doffing."

The construction and operation are as follows:

On the inside of the ring-rail *a*, (see fig. 4,) is placed the bar *o*, suspended to the rail by the links *e e*, so that, when moved endways, it will be raised into the position shown by dotted lines in fig. 4, bringing the projections *s s* up under the bobbin-heads in the rings.

On the outside of the ring-rail *a*, (see fig. 5,) are the devices for separating the thread into two parts. *t* is a stationary cutter or catch, and *d* is the moving one. These cutters or catches are made with sharp edges or notches, which catch the yarn, as the bobbin falls off in front, and cut or separate it, so as to leave an end of the yarn to wind around the empty bobbin. The yarn may also be separated by rubbing it between two surfaces, (see *y*, fig. 5,) the yarn being caught between two parts, which slide one upon the other, whereby the twist is taken out on one side, and the yarn is separated with the least pull.

A sliding bar, *g*, is fastened on the top or back of the ring-rail *a*, (see fig. 5,) having projections on one side, to stop the traveller on the ring, when on the back or behind the spindle, so that, when the bobbins fall off in front, the end of yarn may lie across the flange that held the bobbin. The bar is slid endways, to bring the projections against the ring, so as to stop the traveller. This bar may be hinged to the back of the rail *a*, so as to turn up against the ring and accomplish the same object.

A rail or bar, *k*, (see figs. 3 and 6,) having springs, *b b*, to hold the empty bobbins *c*, is placed behind the spindles, and supported on the arms *l l*, (see fig. 3,) which are pivoted at one end to the bar, and at the other to the slotted knees *x x*, so as to be movable in two ways, one up and down, and the other swinging in and out on the arms.

z z are knee-levers; one end of which is fastened to the slotted knees *x x*, and the other ends are connected together by a rod, *p*, so that they may all move alike.

The whole of this apparatus, for holding and putting on the empty bobbin, is supported by the curtain *A*, or by standards from the under side of the frame *D*, by pins in the slotted knees *x x*, and pivots in the angles of the knee-levers *z z*.

The operation is as follows:

When the bobbins are ready to be "doffed," the machine is stopped, when the ring-rail is at the lowest part of its motion, and the bar *g*, fig. 5, is drawn a little endways, until the projections on it touch the rings, when a little backward motion is given to the driving-cylinder to bring the travellers against the projections; then, by drawing the bar *o*, fig. 4, endways, until the projections upon it come up under the heads of the bobbins, and

by pressing on the lever r , (which is fastened to the lifting-apparatus of the rail,) with the foot, the ring-rail α will be raised, and with it all the bobbins on the spindles B , until they are high enough to fall off, which they will do in front, if the projections on bar o are under the back edge of the bobbin-heads, and draw the yarn across the rings from the traveller, which was stopped at the back of the ring; and the yarn will also lie between the two pieces, $t d$, one of which, d , being slid endways, the yarn will be separated.

Now, by moving the lower end of lever v to the left, the bar p will move the knee-levers $z z$; and raise the slotted knees $x x$. When these reach the limit of their motion, the end of lever v will move the rail k , swinging it out on its arms, so as to bring the empty bobbins e on it over the tops of the spindles B , when, by reversing the motion of the levers v , the whole will first be moved down, so as to bring the bobbins on to the spindles, and then the rail k will be swung back, leaving the bobbins on the spindles, and also on the end of the yarn which lies across the ring, so that upon starting the machine, the yarn will be wound around the bobbins $e e$.

When the full bobbins fall from the spindles, they are caught in a box or trough suitably placed for that purpose, and the device for parting the yarn may be put on the edge of this trough, or on a bar between the trough and ring-rail α , if preferred; and the bar, with projections for stopping the travellers, may be placed on a separate bar back of the ring-rail.

These separate motions may be more or less connected together, so as to leave but few primary motions, or the whole of them may be connected in various ways, so as to be produced at regular intervals by the same power that drives the machine, making it an automatic "doffer."

Having thus described our invention, what we claim, and desire to secure by Letters Patent, is—

1. The combination of the bar o , or its mechanical equivalent, with the ring-rail, for the purpose of throwing off the empty bobbins, substantially as herein set forth.
2. The combination, with a spinning-machine, substantially as described, of the notched bar and sliding thread-separator.
3. The rail k , and the mechanism for operating it, all constructed substantially as described, and for the purpose set forth.

JAMES E. HOOPER,
BENJAMIN ARNOLD.
